(57) **ABSTRACT**

A Modular Pallet System for storage and transport of goods, assembled using Stringer Assemblies comprising 2 or more elongate members that translate in relation to each other to facilitate location and clamping of wood, composite or metal Deck Boards. Stringer Assemblies are assembled from 2 or more elongate members that translate in relation to each other to facilitate location and clamping of Deck Boards. Deck Boards can be manufactured from wood, composite or metal. Clamping action can be achieved by screw, wedge, cam or other mechanical means.

MODULAR PALLET SYSTEM

FIELD OF THE INVENTION

The invention relates, generally, to the field of freight, warehousing, logistics and storage. Specifically, the invention relates to a Pallet for the storage and transport of goods.

BACKGROUND OF THE INVENTION

Wood Pallets form the backbone of the freight and logistics industry, with over 2 billion Pallets in circulation in the United States and 5 billion Pallets globally. The life cycle of a wooden Pallet, however, can be quite brief as supported by the 750 million Pallets manufactured annually in the United States.

Wood is an ideal Pallet material as it is low cost, readily available, light weight, relatively strong and easily processed. Wood "Stringer Pallets" are comprised of 2 or more wood "Stringers" that form the basic internal structure of the Pallet. "Deck Boards" are secured perpendicularly to the upper and lower surfaces of the Stringers. Based on cost and speed of manufacture, wood Pallet components are customarily joined with nails. Stringer Pallets generally utilize 80-120 nails with the final structure able to support heavy loads and facilitate movement using forklifts, Pallet jacks or other motorized equipment.

Common defects associated with nails used to assemble wood Pallets include:

Nail head pull through

Nail pull out

Splitting of Deck Boards or other Pallet structural members

Nails, although low cost and fast to install, are the primary cause of Pallet defects and are also the primary obstacle to the repair, refurbishment, reconfiguration, disassembly and disposal of wood Pallets. Further, the basic design and function of wood Pallets does not lend itself to nesting of Pallets and thus requires a large volume required to store and ship.

Eliminating nails from the manufacture of wood Pallets presents a wide range of opportunities including improved repair and refurbishment, extension of service life, ability to reconfigure and improved options for storage, shipping and disposal.

The proposed invention is a Modular Pallet System that utilizes a simple clamping mechanism to eliminate nails traditionally used for the assembly of Pallet structural members. The clamping action is achieved by the opposed translation of adjacent, nested or telescoping structural members. The preferred embodiment comprises nested metal components and the method of actuation is based on threaded fasteners, but actuation could also be achieved by cam, wedge or other mechanical means.

The clamping Stringer system described above provides the basis of a Modular Pallet System. The ability to rapidly assemble and disassemble Pallets is a new paradigm for the Pallet industry and addresses many of the problems associated with wood Pallets.

BRIEF SUMMARY OF THE INVENTION

The invention teaches a Modular Pallet System comprised of Stringer Assemblies and Deck Boards. Stringer Assemblies are assembled from 2 or more elongate members that, when actuated, translate in relation to each other to facilitate location and clamping of Deck Boards. Deck Boards can be

2

manufactured from wood, polymer, composite or metal. Clamping action on Deck Boards can be achieved by screw, wedge, cam or other mechanical means. Clamping action precludes nails or other such fasteners, which facilitates rapid disassembly and reassembly of the Modular Pallet Assembly. Ability to disassemble and reassemble Modular Pallet Assembly facilitates fast and low-cost repair or reconfiguration for different applications that may require different Deck Board materials or change in load capacity. Components are designed, where possible, to stack and nest, providing compact packaging for shipping and storage.

As Pallets can be rapidly disassembled and reassembled, bulk Pallet components can be stored in a compact configuration and assembled "on demand". For example, Pallet components can be manufactured and shipped in bulk to factory setting and assembled when required to load and ship products. Pallets can then be disassembled at point of purchase where the large size and bulk of a Pallet presents a hinderance to commerce. Bulk Pallet components can be stored in a compact configuration for future use or returned and recycled for future use.

When damaged or at end of service life, Pallet can be safely and easily disassembled with components recycled or disposed of as appropriate.

Benefits of proposed Modular Pallet System:

Elimination of nails eliminates primary source of damage to Palletized goods

Elimination of nails prevents Deck Boards splitting, thus extending Pallet service life

Rapid disassembly/reassembly of Pallet facilitates repair and refurbishment of damaged Pallets at any point in supply chain, without special equipment or training

Unassembled Stringer components and Deck Boards provide very compact configuration for shipping and storage

Pallets can be easily reconfigured to accept Deck Boards manufactured from different materials, including wood, plastic, metal or other materials

Pallets can be easily reconfigured to vary load capacity, by varying number and location of Stringer Assemblies

Pallets can be easily reconfigured to change width dimension of Pallet by using Deck Boards of different length

Pallets can be easily disassembled for cleaning, sterilization and reassembly when necessary

Pallets can be easily disassembled and components recycled or scrapped

Additional benefits provided by the modular Stringer systems includes ability to attach accessories such as caster wheels, handles and other components that provide increased versatility and value of the proposed Modular Pallet System.

FIG. 63 depicts (1) Modular Pallet Assembly with stacked and nested Inner and Outer Stringer Channels and stacked Wood Deck Boards comprising components for (40) Pallet Assemblies

FIG. 64 depicts (1) Modular Pallet Assembly with stacked and nested Inner and Outer Stringer Channels and stacked

and nested formed Metal Deck Boards comprising components for (40) Pallet Assemblies

DETAILED DESCRIPTION OF THE INVENTION

It is specifically intended that the present invention not be limited to the embodiments and illustrations contained herein, but include modified forms of those embodiments including portions of the embodiments and combinations of elements of different embodiments as come within the scope of the following claims.

Referring to FIGS. 1-15, the Modular Pallet Assembly consists of (2) or more Stringer Assemblies and a multitude of Deck Boards. The system is configured to accept Deck Boards of various designs and materials, to accommodate a wide range of industries and applications.

Referring to FIGS. 1-4 and FIG. 13, (3) Stringer Assemblies 1 locate and secure (14) Wood Deck Boards 2. Wood Deck Boards are utilized for commodity applications such as consumer products and industrial components.

Referring to FIGS. 5-8 and FIG. 14, (3) Stringer Assemblies 1 locate and secure (14) extruded polymer, composite or metal Deck Boards 3. Extruded polymer, composite or metal Deck Boards are commonly utilized for sterile applications, such as shipping of medicines and pharmaceuticals or where the danger of wood-borne pests is a concern.

Referring to FIGS. 9-12 and FIG. 15, (3) Stringer Assemblies 1 locate and secure (14) formed Metal Deck Boards 4. Metal Deck Boards are generally utilized for high load and longer term applications such as military and industrial equipment.

Referring to FIGS. 16-18 and FIG. 26, the preferred embodiment of the Stringer Assembly 12 is comprised of 2 elongate, nesting Channels. Alternate embodiments of the Stringer Assembly could include telescoping tubes of various shapes, parallel plates, straight sided channels, nesting hat sections, other shapes and various combinations thereof.

Outer Channel 13 and Inner Channel 14 fit closely, providing secure location and transfer of forces, but are able to freely translate along their length.

Spring Button 19, can be rapidly installed and removed without the use of tools, is installed through slot 33 in Outer Channel and hole 48 in Inner Channel. Spring Button 19, secures Inner Channel and Outer Channel together and controls range of translation. With Spring Button 19 at one end of translation, Deck Boards can be properly inserted. With Spring Button 19 at other end of translation, maximum compression of Deck Boards is controlled.

Bolt Plate 16 is inserted transversely through straight slot 27 in Outer Channel 13 and through clearance slot 41 in Inner Channel 14

Nut Plate 18 is inserted transversely through clearance slot 26 in Outer Channel 13 and straight slot 40 in Inner Channel 14.

Bolt 15 is assembled through Bolt Plate 16, through Nut Plate 18 and into Captive Nut 17.

Captive Nut 17, which can be installed and removed without tools, is secured to Nut Plate 18.

It should be noted that, for low cost and minimal complexity, Bolt Plate 16 and Nut Plate 18, although serving different functions, are the same component and are differentiated here only for clarity of function.

Referring to FIG. 20-22, note Outer Channel 13 and Inner Channel 14 are shown in an unclamped configuration with Outer Channel Upper Protrusions 31 and Inner Channel Upper Protrusions 46 aligned. Also aligned are Outer Chan-

nel Lower Protrusions 24 and Inner Channel Lower Protrusions 38. In this configuration, Deck Boards can be installed into recesses on the upper and lower surfaces of the Stringer Assembly. In this configuration, Bolt 15 is unactuated and assembled through Bolt Plate 16 and Nut Plate 18 and threaded into Captive Nut 17.

Referring to FIG. 23-25, note Outer Channel 13 and Inner Channel 14 are shown in a clamped configuration with Outer Channel Upper Protrusions 31 and Inner Channel Upper Protrusions 46 not aligned. Also not aligned are Outer Channel Lower Protrusions 24 and Inner Channel Lower Protrusions 38. In this configuration, Bolt 15 is actuated and assembled through Bolt Plate 16 and Nut Plate 18 and threaded into Captive Nut 17. In this configuration, Deck Boards are clamped in the upper and lower recesses of the Stringer Assembly.

Referring to FIG. 26, the simplicity of the Stringer Assembly is depicted with (7) components and (6) unique part numbers. All Stringer Assembly components can be assembled, disassembled, inspected and reassembled without the use of tools, a significant benefit in a Warehouse environment. The only tool required to assemble or disassemble the Modular Pallet Assembly is a powered or manual wrench.

Referring to FIGS. 27-30, the basic structure of the Outer Channel consists of Side Walls 21 connected by Top Surface 20. Note that angled Side Walls 21 of Channel provide the necessary bending strength while also facilitate nesting in a stacked configuration, providing stable and compact storage of components.

Outer Channel 13 can be manufactured from metal or polymer, but preferred embodiment is light gauge steel. Laser cutting can be utilized for lower production volumes with stamping preferred for higher volumes.

Recesses 25 are configured to receive Forklift Forks.

Hole 28 is alternate location for Spring Button 19 and can also be used to locate and secure accessories such as Caster Wheels and Handles, adding functionality for applications such as the Grocery market.

Straight slot 27 receives Bolt Plate 16, which does not translate in relation to Outer Channel 13.

Elongated slot 26 receives Nut Plate 18, which translates in relation to Outer Channel 13.

Upper Deck Board Recess 29 vertically locates and supports all types of Deck Boards.

Angled Recess Surfaces 30 provide a clamping surface for metal and extruded Deck Boards.

Protrusions 31 are formed at both ends of all Upper Deck Board Recesses 29 and serve different functions depending on type of Deck Board. For thicker Wood Deck Boards with vertical side surfaces, Protrusion 31 penetrates Wood Deck Board side surfaces 63 when clamped, locating and securing them. For thin Wood Deck Boards with vertical side surfaces, Protrusions 31 secures Deck Board in Upper Deck Board Recesses 29 and clamping force is provided by Angled Recess Surfaces 30. For Deck Boards with grooved side surfaces, such as those depicted in FIG. 47-54, Protrusions 31 are configured to locate and clamp into the groove features, providing location and resistance to vertical forces. Protrusions 31 locate and secure Metal Deck Boards in Upper Deck Board Recesses 29 using slot 82, depicted in FIGS. 59-62.

Angled Side Surfaces 30 of Upper Deck Board Recesses 29 apply clamping forces to all Deck Boards with angled sided surfaces, including Wood Deck Board with angled side surfaces depicted in FIGS. 43-46, Extruded Deck Board

depicted in FIG. 51-54, alternate design Extruded Deck Board depicted in FIGS. 55-58 and Metal Deck Board depicted in FIGS. 59-62.

Lower Deck Board Recess 22 vertically locates and supports all types of Deck Boards.

Angled Recess Surfaces 23 provide a clamping surface for metal and extruded Deck Boards.

Protrusions 24 are formed at both ends of all Lower Deck Board Recesses 22 and serve different functions depending on type of Deck Board.

For Wood Deck Boards with vertical side surfaces, Protrusion 24 penetrates Wood Deck Board side surfaces 63 when clamped, locating and securing them.

For Deck Boards with grooved side surfaces, such as those depicted in FIG. 47-54, Protrusions 24 are configured to locate and clamp into the groove features, providing location and resistance to vertical forces

Protrusions 24 locate and secure Metal Deck Boards in Lower Deck Board Recesses 22 using slot 81, depicted in FIGS. 59-62.

Angled Side Surfaces 23 of Lower Deck Board Recesses 22 apply clamping forces to all Deck Boards with angled sided surfaces, including Wood Deck Board with angled side surfaces depicted in FIGS. 43-46, Extruded Deck Board depicted in FIGS. 51-54, alternate design Extruded Deck Board depicted in FIGS. 55-58 and Metal Deck Board depicted in FIGS. 59-62.

Slot 30 receives Spring Button depicted in FIG. 38 and serves to limit range of translation between Outer Channel 13 and Inner Channel 14.

Slot 32 creates a cantilever spring for protrusion, providing ability to control deflection and load transfer to individual Deck Boards when clamping force is applied. This controlled force and deflection allows for Deck Boards of slightly varying widths, which can be the result of manufacturing tolerances or the loss or gain of moisture in Wood Deck Boards.

Note that the Outer Channel is symmetric end-to-end, preventing improper assembly into Stringer Assembly. Mirrored features also provide redundancy for damaged features, providing a more robust component in a warehouse environment.

Referring to FIGS. 31-34, the basic structure of the Inner Channel consists of Side Walls 35 connected by Top Surface 34. Note that angled Side Walls 35 of Channel provide the necessary bending strength while also facilitate nesting in a stacked configuration, providing stable and compact storage of components.

Inner Channel 13 can be manufactured from metal or polymer, but preferred embodiment is light gauge steel. Laser cutting can be utilized for lower production volumes with stamping preferred for higher volumes.

Slot 42 provide clearance for alternate location of Spring Button 19.

Elongated slot 41 receives Bolt Plate 18, which translates in relation to Inner Channel 14.

Recesses 39 are configured to receive Forklift Forks.

Straight slot 40 receives Nut Plate 16, which does not translate in relation to Inner Channel 14.

Upper Deck Board Recess 44 vertically locates and supports all types of Deck Boards.

Angled Recess Surfaces 45 provide a clamping surface for metal and extruded Deck Boards.

Protrusions 46 are formed at both ends of all Upper Deck Board Recesses 44 and serve different functions depending on type of Deck Board. For thicker Wood Deck Boards with vertical side surfaces, Protrusion 46 penetrates Wood Deck

Board side surfaces 63 when clamped, locating and securing them. For thin Wood Deck Boards with vertical side surfaces, Protrusions 46 secures Deck Board in Upper Deck Board Recesses 44 and clamping force is provided by

5 Angled Recess Surfaces 45. For Deck Boards with grooved side surfaces, such as those depicted in FIG. 47-54, Protrusions 46 are configured to locate and clamp into the groove features, providing location and resistance to vertical forces. Protrusions 46 locate and secure Metal Deck Boards in 10 Upper Deck Board Recesses 29 using slot 81, depicted in FIGS. 59-62.

Angled Side Surfaces 45 of Upper Deck Board Recesses 44 apply clamping forces to all Deck Boards with angled sided surfaces, including Wood Deck Board with angled side surfaces depicted in FIGS. 43-46, Extruded Deck Board depicted in FIG. 51-54, alternate design Extruded Deck Board depicted in FIGS. 55-58 and Metal Deck Board depicted in FIGS. 59-62.

20 Lower Deck Board Recess 36 vertically locates and supports all types of Deck Boards.

Angled Recess Surfaces 37 provide a clamping surface for metal and extruded Deck Boards.

Protrusions 38 are formed at both ends of all Lower Deck 25 Board Recesses 36 and serve different functions depending on type of Deck Board.

For Wood Deck Boards with vertical side surfaces, Protrusion 38 penetrates Wood Deck Board side surfaces 63 when clamped, locating and securing them.

30 For Deck Boards with grooved side surfaces, such as those depicted in FIG. 47-54, Protrusions 38 are configured to locate and clamp into the groove features, providing location and resistance to vertical forces

Protrusions 38 locate and secure Metal Deck Boards in 35 Lower Deck Board Recesses 22 using slot 81, depicted in FIGS. 59-62.

Angled Side Surfaces 37 of Lower Deck Board Recesses 36 apply clamping forces to all Deck Boards with angled sided surfaces, including Wood Deck Board with angled side surfaces depicted in FIGS. 43-46, Extruded Deck Board depicted in FIG. 51-54, alternate design Extruded Deck Board depicted in FIGS. 55-58 and Metal Deck Board depicted in FIGS. 59-62.

45 Hole 48 receives Spring Button 19 depicted in FIG. 38 and serves to limit range of translation between Outer Channel 13 and Inner Channel 14.

Slot 47 creates a cantilever spring for protrusion, providing ability to control deflection and load transfer to individual Deck Boards when clamping force is applied. This controlled force and deflection allows for Deck Boards of slightly varying widths, which can be the result of manufacturing tolerances or the loss or gain of moisture in Wood Deck Boards.

55 Note that the Inner Channel is symmetric end-to-end, preventing improper assembly into Stringer Assembly. Mirrored features also provide redundancy for damaged features, providing a more robust component in a warehouse environment.

Referring to FIG. 35, the basic structure of the Bolt Plate 16 and Nut Plate 18 is a robust planar body 49 with the necessary bending and shear strength required to resist the large clamping forces applied by Bolt 15 and Captive Nut 17. Bolt Plate 16 or Nut Plate 18 can be manufactured from 60 metal, but the preferred embodiment is 0.25 in. thick mild steel. Laser cutting can be utilized for lower production volumes with stamping preferred for higher volumes.

The internal square hole **50** is configured to receive Captive Nut **17** but also provides the required clearance to facilitate installation of Bolt **15**.

Surfaces **54** provides a large area to grip between thumb and forefinger during manual insertion and removal of Bolt Plate **16** and Nut Plate **18** into Stringer Assembly **1**.

Surfaces **54** also provides a large surface area to distribute clamping forces to slot **27** on Outer Channel and slot **40** on Inner Channel. Surface **54** surface must be long enough to produce bearing pressures on edges of slots **27** and **40** less than material yield strength of either Bolt Plate **16**, Nut Plate **18**, Outer Channel **13** or Inner Channel **14**.

Surfaces **51** locate the Bolt Plate and Nut Plate vertically in slot **27** on Outer Channel and in slot **40** on Inner Channel.

Surfaces **52** provide a transition to an increased section at the midspan of the component where bending stresses are highest. Surfaces **52** are angled to provide clearance for translation inside Side Walls Inner Channel **14**. Refer to FIG. **16** for more information.

Note that Bolt Plate **16** and Nut Plate **18** has multiple axes of symmetry, preventing improper assembly into Stringer Assembly **1**.

Referring to FIG. **36**, Bolt **15** is a commercially available threaded fastener. The preferred embodiment is nominally a $1/2\text{-}13$ Grade 5 Hex Washer Head Bolt.

Hex feature **55** provides robust method of actuation for installation, removal and clamping Deck Boards.

Washer Head feature **56** provides a large surface to distribute loads against surface **49** of Bolt Plate.

Screw threads **57** are inserted into Nut **17** to provide method of translating Outer Stringer **13** and Inner Stringer **14** and applying clamping loads to Deck Boards.

Referring to FIG. **37**, Captive Nut **37** is a commercially available Nut. The preferred embodiment is a $1/2\text{-}13$ Grade 2 Cage Nut.

Screw threads **58** receive threads **57** on Bolt **15**.

Spring loaded fingers **59** are manually compressed with thumb and forefinger to facilitate installation and removal of Captive Nut into internal square hole **50** of Nut Plate **18**.

Referring to FIG. **38**, Spring Button Assembly **19** is a commercially available component utilized for various purposes such as connecting telescoping tubing.

The Spring Button Assembly can be installed and removed without tools by compressing Pins **61** between thumb and forefinger, thereby flexing body **60** and withdrawing Pins **61** from slot **33** in Out Channel **13** and hole **48** in Inner channel **14**.

The preferred embodiment of Spring Button Assembly **19** includes Pins **61** approximately 0.375 in. in diameter and 0.375 in. in length.

Referring to FIG. **39-42**, Wood Deck Board **2** is a commercially available hardwood or softwood Deck Board, commonly used for manufacturing wood Pallets.

Top Surface **62** provides support for packages loaded on Modular Pallet Assembly or is located in Lower Deck Board Recesses **22** of Outer Channel or Lower Deck Board Recesses **36** of Inner Channel to provide support on grade.

Bottom Surface **64** provides support for Modular Pallet Assembly on grade or is located in Upper Deck Board Recesses **29** of Outer Channel **13** or Upper Deck Board Recesses **44** of Inner Channel **14**.

Vertical Side Surfaces **63** are clamped and located by protrusions **31** on Outer Channel **13** or protrusions **46** on Inner Channel **14**.

Referring to FIG. **43-46**, Wood Deck Board with Chamfered Side Surfaces is manufactured from hardwood or softwood.

Top Surface **65** provides support for packages loaded on Modular Pallet Assembly or is inverted and located in Lower Deck Board Recesses **22** of Outer Channel or Lower Deck Board Recesses **36** of Inner Channel to provide support on grade. Board thickness is such that Top Surface **65** is retained under Protrusions **31** on Outer Channel **13** and Protrusions **46** on Inner Channel **14**.

Bottom Surface **67** is located in Upper Deck Board Recesses **29** of Outer Channel **13** and Upper Deck Board Recesses **44** of Inner Channel **14**. Bottom Surface **67** is located in Outer Lower Deck Board Recesses **22** Inner Lower Deck Board Recesses **36** to provide support for Modular Pallet Assembly.

Deck Board Angled Side Surfaces **66** are clamped by Angled Side Surfaces **30** of Upper Deck Board Recesses **29** in Outer Channel **13**, Angled Side Surfaces **23** of Lower Deck Board Recesses **22** in Outer Channel **13**, Angled Side Surfaces **45** of Upper Deck Board Recesses **44** in Inner Channel **14** and Angled Side Surfaces **23** of Lower Deck Board Recesses **36** in Inner Channel **14**.

Referring to FIG. **47-50**, Deck Board with grooved side surfaces can be manufactured from milled wood, extruded polymer, extruded composite or extruded metal.

Top Surface **68** provides support for packages loaded on Modular Pallet Assembly or is located in Lower Deck Board Recesses **22** of Outer Channel **13** or Lower Deck Board Recesses **36** of Inner Channel **14**.

Bottom Surface **69** provides support for Modular Pallet Assembly on grade or is located in Upper Deck Board Recesses **29** of Outer Channel **13** or Upper Deck Board Recesses **44** of Inner Channel **14**.

Grooved Side Surfaces **70** are configured to receive and be clamped and located by protrusions **31** and **24** of Outer Channel **13** and protrusions **46** and **38** of Inner Channel **14**.

Referring to FIG. **51-54**, Extruded Deck Board with Grooved Sides can be manufactured from extruded polymer, extruded composite or extruded metal.

Top Surface **71** provides support for packages loaded on Modular Pallet Assembly or is inverted and located in Lower Deck Board Recesses **22** of Outer Channel **13** and Lower Deck Board Recesses **36** of Inner Channel **14** to provide support on grade.

Grooved Side Surfaces **72** are configured to receive and be clamped and located by protrusions **31** and **24** of Outer Channel **13** and protrusions **46** and **38** of Inner Channel **14**.

Angled Side Surfaces **73** are clamped by Angled Side Surfaces **30** of Upper Deck Board Recesses **29** in Outer Channel **13**, Angled Side Surfaces **23** of Lower Deck Board Recesses **22** in Outer Channel **13**, Angled Side Surfaces **45** of Upper Deck Board Recesses **44** in Inner Channel **14** and Angled Side Surfaces **23** of Lower Deck Board Recesses **36** in Inner Channel **14**.

Surfaces **74** are removed areas to reduce weight and cost.

Stiffening Rib **75** increases strength and rigidity with minimal additional cost and weight.

Referring to FIG. **55-58**, alternate design extruded Deck Board can be manufactured from polymer, extruded composite or extruded metal.

Top Surface **76** provides support for packages loaded on Modular Pallet.

Top Surface **76** can be inverted and Deck Board located in Lower Deck Board Recesses **22** of Outer Channel **13** and Lower Deck Board Recesses **36** of Inner Channel **14** to provide support on grade.

Angled Side Surfaces **78** are clamped by Angled Side Surfaces **30** of Upper Deck Board Recesses **29** in Outer Channel **13**, Angled Side Surfaces **23** of Lower Deck Board

11

Recesses **22** in Outer Channel **13**, Angled Side Surfaces **45** of Upper Deck Board Recesses **44** in Inner Channel **14** and Angled Side Surfaces **23** of Lower Deck Board Recesses **36** in Inner Channel **14**.

Referring to FIG. **59-62**, Metal Deck Board can be manufactured from light gauge metal. The preferred embodiment is light gauge steel, laser cut or stamped and formed.

Top Surface **79** provides support for packages loaded on Modular Pallet.

Top Surface **76** can be inverted and Deck Board located in Lower Deck Board Recesses **22** of Outer Channel **13** and Lower Deck Board Recesses **36** of Inner Channel **14** to provide support on grade.

Angled Side Surfaces **80** are clamped by Angled Side Surfaces **30** of Upper Deck Board Recesses **29** in Outer Channel **13**, Angled Side Surfaces **23** of Lower Deck Board Recesses **22** in Outer Channel **13**, Angled Side Surfaces **45** of Upper Deck Board Recesses **44** in Inner Channel **14** and Angled Side Surfaces **23** of Lower Deck Board Recesses **36** in Inner Channel **14**.

Slot **82** provides location for Protrusion **31** on Outer Channel **13** and Protrusion **46** on Inner Channel **14**.

Slot **81** provides location for Protrusion **24** on Outer Channel **13** and Protrusion **38** on Inner Channel **14**.

Referring to FIG. **63**, this depicts the storage of Outer Channels **13**, Inner Channels **14** and Wood Deck Boards **2** required to assemble (40) Modular Pallet Assemblies. Not shown are smaller components Bolt **15**, Bolt Plate **16**, Nut Plate **18**, Captive Nut **17** and Spring Button Assembly **19**.

Referring to FIG. **64**, this depicts the storage of Outer Channels **13**, Inner Channels **14** and Metal Deck Boards **4** required to assemble (40) Modular Pallet Assemblies. Not shown are smaller components Bolt **15**, Bolt Plate **16**, Nut Plate **18**, Captive Nut **17** and Spring Button Assembly **19**.

Referring to FIGS. **22**, **25** and **26**, opposing translation of Outer Channel **13** and Inner Channel **14** and resulting clamping force on Deck Boards is caused by clockwise rotation of Bolt **15**, which screws into Captive Nut **17**. Face of Bolt **15** applies force to Bolt Plate **16** which applies force to slot **27** in Outer Channel **13**. Simultaneously, Captive Nut **17** applies an equal and opposite force to Nut Plate **18**, which applies force to slot **40** in Inner Channel **14**.

The magnitude of clamping force is proportional to the torque applied to Bolt **15**. Using an easily attainable 50 ft.-lbs. of torque applied to the preferred embodiment of a Grade 5½-13 bolt results in a clamping force in the range of 5,000-10,000 lbs. per Stringer Assembly.

Dividing this clamping force by the number of contact points on Deck Boards results in forces exceeding what properly installed nails can provide. Thus, the clamping force provided by the Stringer Assembly provides superior security of Deck Boards than traditional nails can provide.

As discussed earlier, eliminating nails eliminates the primary source of Deck Board splitting. Further, any pre-existing splits in Deck Boards should be mitigated as Deck Boards are compressed by clamping forces.

Disassembly of the Modular Pallet System can be easily achieved with no tools.

Counterclockwise rotation of Bolt **15** translates Outer Channel **13** in relation to Inner Channel **14** until Spring Button Assembly **19** contacts end of slot **33** in Inner Channel **14**. In this configuration, Deck Boards can be easily removed.

To disassemble Stringer Assemblies, continued counterclockwise rotation allows removal of Bolt **15**. Captive Nut

12

17 can be removed from Nut Plate **18**. Removal of Bolt Plate **16**, Nut Plate **18** and Spring Button Assembly **19** complete disassembly process.

Assemble is achieved by reversing disassembly process.

I claim:

1. A Modular Pallet System for the movement of goods comprising:

a plurality of deck boards;

a plurality of stringer assemblies;

wherein each of the stringer assemblies is constructed from a plurality of parallel elongate members, each elongate member fitted with recesses to accept deck boards; and

wherein plurality of elongate members are configured to translate in relation to each other to apply clamping forces to the deck boards for the purpose of locating and securing the deck boards to provide bracing, structural integrity and load capacity, wherein the translation is achieved by actuation of screw, cam, wedge, or other mechanical means.

2. The system of claim 1, wherein the number and location of stringer assemblies can be varied to vary size and load capacity.

3. The system of claim 1, wherein the deck boards can be fashioned from wood, plastic or metal and are interchangeable.

4. The system of claim 1, wherein the pallet assembly can be disassembled and reassembled for repair, reconfiguration or refurbishment and constituent components packaged for storage and shipping.

5. A stringer assembly for a modular pallet system constructed from a plurality of elongate members;

wherein elongate members are fitted with recesses to accept deck boards; and

wherein the plurality of elongate members are configured to translate in relation to each other to apply clamping forces to the deck boards for the purpose of securement of the deck boards and to provide structural integrity and load capacity, wherein the translation is achieved by actuation of screw, cam, wedge, or other mechanical means.

6. The assembly of claim 5 wherein the elongate members are fashioned from wood, plastic or metal; and

wherein the elongate members can be formed from tubular members, planar shapes, channels, tapered channels, hat sections, angles or other common structural shapes.

7. The assembly of claim 6, wherein the elongate members are fitted with slots to accept forklift forks.

8. The assembly of claim 5, wherein extents of translation of the elongate members are limited by slots to provide an open position from installation of deck boards and a maximum translation position to prevent over-clamping or crushing of deck boards.

9. The assembly of claim 5 wherein the elongate members are formed from steel channels with sloped side surfaces to facilitate stacking of nested elongate members.

10. The assembly of claim 9, wherein the recesses in the elongate members have non-vertical sloping surfaces configured to receive mating non-vertical sloping surfaces of the deck boards.

11. The assembly of claim 9, wherein the recesses in the elongate members are configured with shaped protrusions, serrations, or texture to engage and secure the deck boards.

12. The system of claim 9, wherein the deck boards are fashioned from wood, plastic or metal with constant section along a length and are fashioned with continuous or inter-

mittent grooves or slots along the length to engage the non-vertical sloping surfaces of the elongate members.

13. The assembly of claim **5** wherein the elongate members are configured with openings to accept deck boards.

14. The system of claim **1**, wherein the deck boards have ⁵ sloped side surfaces to facilitate securement to the stringer assembly.

15. The system of claim **1**, wherein the deck boards are fashioned from wood, plastic, or metal with a constant section along a length, and wherein the deck boards have ¹⁰ non-vertical sloping surfaces to facilitate nesting of deck boards.
